(57) **CLAIM**

The ornamental design for a lever handle inlaid with semi-precious stones or gems on top with brass base, as shown and described.

DESCRIPTION

FIG. 1 is a perspective view of a lever handle inlaid with semiprecious stones or gems on top with brass base, showing my new design;

FIG. 2 is a right side view thereof;

FIG. 3 is a top view thereof;

FIG. 4 is a bottom view thereof;

FIG. 5 is a rear view thereof; and,

FIG. 6 is left side view thereof.

The broken lines shown represent unclaimed subject matter and form no part of the claimed design.

1 Claim, 6 Drawing Sheets
